METHOD AND APPARATUS FOR WINDING BALLS

Frank Honig, Pawtucket, R. I.

Application May 12, 1936, Serial No. 79,252

13 Claims. (Cl. 242—3)

This invention relates to the art of winding filaments, particularly to holding cores of spherical or similar shape while winding some filamentary or tape-like material thereon to produce articles such as base balls, golf balls and the like, and the object of the invention is the provision of improvements in this art.

The present application constitutes a continuation in part of my application Serial Number 47,732, filed November 1, 1935, now Patent No. 2,138,452, which discloses a method of producing wound spherical objects and the resultant product. The present specification is directed to the holding of the product during winding according to the method therein described.

Some of the more specific objects of the invention are: to provide a very simple method of and apparatus for holding the core while it is driven to produce convolutions thereon; to provide means for changing the lay of, i. e., the pattern formed by, the convolutions on the core; to provide means for maintaining uniform pattern if so desired; to provide means for winding on soft cores with rapid coverage; to provide means for winding on hard cores with slow coverage; to provide means to vary the coverage from slow to rapid during the winding of a core; and, to provide other advantages and new features which will be evident as the description of the invention proceeds.

According to the present invention the spherical core is held in a pocket or cup-like cavity formed by several rotatably mounted idlers, of some suitable shape, which are free to rotate, as they are driven by the core itself, in one or more directions, or at different rates of speed, from time to time, of each rotatable member, and with relation of one member to the others. That is, each rotatable member is independent of all the others; each member may rotate faster or slower, or to the right or to the left of some of the other members; or it may swing back and forth about a pivot, or slide endwise in either direction. Some of the rotatable members may have two or more directional motions besides the free rotation. Each motion is, however, free motion.

Considering all the rotatable members forming the cup-like pocket as a unit system, then each and every member has a constantly changing direction and speed of rotation with relation to any of the other members. These changes may proceed from portion to portion of a single convolution as it is wound on the core, and also from convolution to convolution in winding a single ball. However, the range or amplitude remains constant in both the positive and negative direction in any one device at any one setting and may be modified to increase or decrease the amplitude by adjustment either during the opera-

tion of the device or at any other time, as will be described.

It may be stated here, that the maximum change of speed of the rotatable members in a single convolution on the core may be from the maximum positive amplitude to the maximum negative amplitude and is gradual. When it is considered that the average golf ball, for example, has over 2100 convolutions wound on a core, then it will be evident that the relative speed and directional changes in the rotative members, practically speaking, is infinite. The driving of the core, in such manner as to form a suitable pattern on the core is disclosed in the above-identified application.

This invention, however, embraces mechanism which can receive and maintain a fixed pattern from an independent driving mechanism through the core being wound, and through such core only. Also, it can receive a fixed pattern and gradually but continuously change that pattern during the winding of a single core and maintain such system of change from core to core. By such variation in the pattern system at various stages of the winding of a core there can be produced harder or softer layers of winding on any one particular core; also, by starting with closely spaced or dense layers of convolutions at the beginning and gradually opening up the layers of convolutions from one another, a very hard ball can be produced and at the same time the top layer or layers will be suitably separated to form a pattern advantageous to produce the desired amalgamation of any cover as may be placed over the wound core. Previous to my present invention this variation in the pattern of winding on a core was produced:

1. By winding the core partially on one type winding machine with close pattern characteristics and then winding the top layers on a separate machine of some different type with open pattern characteristics. Thus two operations were required to produce the wound core.

2. By providing, in a machine primarily intended for winding on a pattern of close characteristics, some highly complicated mechanism which entirely changes the winding characteristics to produce the open pattern at the outer surface of the wound core. Such a combination machine has many of the disadvantages of separate machines and in many respects may be less convenient to use than separate machines.

In contradistinction, my present invention provides simple mechanism which will, if so desired, gradually and progressively change the pattern of winding from close spacing to open spacing or vice versa. This, as will be seen from the following description, is accomplished by making use of the inherent increase in the diameter of the core being wound to change its own axis of

rotation in that plane which controls the pattern or spacing of the convolutions on the core.

This change or shift in the axis of rotation in the pattern control plane is accomplished by the 5 suitable arrangement or relative location of the supporting idlers, in their freedom of rotation, or other movement, as transmitted to them and controlled by the core itself as it is being wound. No mechanism to drive these supporting members 10 is required, nor is it possible, practically speaking, to provide any suitable driving mechanism such as would produce the highly complex and constantly changing relative speed and directional combination as demanded by the core being 15 wound to produce thereon the constantly changing pattern of winding as the axis of rotation is changed.

It may be explained that this invention forms an adjunct to ball winding machines of the general type shown in my copending application, 20 Serial Number 79,251 filed May 12, 1936 and to the several species of this general type. This invention is operative only in such ball winding machines where a single driving member contacting the core approximately at a single point 25 is employed to drive the core, provided however, that such single driving member has two or more directional motions incorporated therein.

For convenience of description we may refer 30 to the sphere being wound as if it were the earth. At a given moment the circle of rolling will be called the polar circle; the circle at right angles to the polar circle and passing through the drive point of the sphere at the same given 35 moment will be called the equatorial circle; and the poles will be located where the axis perpendicular to the equatorial plane intersects the polar circle.

In the drawings:

Fig. 16 is a duplicate of Fig. 13 with a third circular motion imposed over the two shown in Fig. 13;

Fig. 17 is an end view of the sphere taken as indicated on line 17—17 of Fig. 16;

Fig. 18 is a plan view of Fig. 17 showing the reciprocating movement caused by the third circular motion; and

Fig. 19 is a side elevation of the sphere showing the reversal of the polarity of the pole axis, and the equatorial distributing circle of Fig. 14 on a somewhat enlarged scale.

Referring first to Fig. 1, member A represents 15 a single driving member to which a resultant driving motion or pattern is imparted, which motion is the result of three separate circular motions interposed over one another, namely, a circular motion represented by a circle passing 20 through the poles of a sphere, a second circular motion represented by a circle coinciding with the equator of the sphere, and a third circular motion represented by a comparatively small circle having its center at one of the points where 25 the polar circle crosses the equatorial circle.

This member A may be the hand of an operator, a disc, a sphere, or any suitable member, and it may be moved in any desired manner suitable to form a sphere. It forms no part of this 30 invention and is shown only as a matter of convenience to illustrate the present invention. Several forms of member A and several ways of driving such member A are shown and fully described in my co-pending applications Serial No. 47,732 35 and Serial No. 79,251 above identified.

The resultant single directional motion so produced in member A is fixed and remains uniform at any one diameter of said member and may be considered as the base or foundation pattern.

40 One of the objects of the present invention is to receive such base pattern from a member A and change or modify it to any desired degree. This change is continuous, and either automatic or manually adjustable as desired, or both automatic and manual, in the winding of a core from the starting to the finishing size.

45 This change of pattern on the core being wound from that which it received from its driving member A is accomplished by a change of the axis of rotation of the equatorial circle of the core. That is, if the driving member A, Fig. 1, drives the core B in such manner that the equator is rotated a given angular turn C for each revolution of the polar circle then the mean pitch of 50 a given convolution G will be the angle indicated at D provided the rotative center of the equatorial circle of core B, which may also be referred to as equatorial circle B, is located at the geometric center of said circle as shown in Fig. 1. In such case the angular pattern of winding on the core remains substantially uniform at all diameters of the core. The developed linear spacing will, however, change so as to maintain 55 such uniform angular pattern.

55 The change in the axis of rotation is in effect a division of one rotative axis of the sphere in one plane. Considering Fig. 3 a sort of plan view of Fig. 9 then the sphere will turn about the focal point where the line E crosses the normal center line of the sphere. At the same time it will turn concentrically with its normal or geometric center in the side elevation shown as Fig. 9.

60 In Fig. 3 the rotative center of the equatorial 75

circle is shown away from the geometric center of said circle and is located on line E. When this is the case, then the geometric center of circle B moves, or reciprocates, as indicated at 5 F, F and the mean pitch of a given convolution G will then be the angle as indicated at D1.

As will be seen, the base pattern as indicated by the angular turn C in both Fig. 1 and Fig. 3 is the same, while the mean pitch of the convolution as indicated at D in Fig. 1 and at D1 in Fig. 3 will vary. D1 is less than D.

Thus, it will be clear from the diagrammatic illustration that if the rotative center of the equatorial circle is changed with relation to its 15 geometric center, then the pattern of winding on the core will also change, notwithstanding the fact that the fundamental or driving pattern will always remain the same in member A as indicated.

20 And, since some of the axes of rotation are moved with relation to the geometric center of the sphere, and since some of the axes do not pass through the geometric center of the sphere in every plane, this invention is capable of operation only when all the motive force to move the ball, in any direction whatsoever, is transmitted to the ball being wound by one and only by one member driving the ball approximately through a single point.

30 The bearing points or contact points at which the core is supported have an important relation to the location, change, or maintenance of the rotative center of the equatorial circle.

The approximate locations of these points are indicated in Fig. 2 and Fig. 4. Thus, in Fig. 2 the lines C1, C1 represent the primary amplitude of angular shift in the equatorial circle, to the right or to the left as the case may be. Lines C2, C2 represent the secondary amplitude of 35 angular shift caused by the interposition of the third circular motion in member A to cause the axis of the core to describe a cone. These lines C2, C2, also represent the maximum amplitude of shift of the core.

45 The contact or supporting points for the core should fall on lines C1 or C2 or between these lines. These points, when located on line C1, are shown with small circles designated as 1, 2, 3 and 4 and represent the points of contact of the holding members shown in Figs. 5 and 6. Points 50 1 and 2 designate the lower pair and points 3 and 4 designate the upper pair or the pair furthest away on the development from the driving point in the direction of drive.

55 In Fig. 5 the lower pair of contact points are located on discs 6 and the upper pair on discs 7. The contact points 1, 2, 3, and 4 of Fig. 2 are located on the lines 1, 2, 3 and 4 of Fig. 6.

60 In Fig. 7 the rotative center of the equatorial circle is located on the circumference of the equatorial circle for the maximum distance away from the geometric center of said circle as when the core is small and rides only on the members 65 37, or on line E as the minimum distance from the geometric center when the core is full size, as shown. It should be noted here that at the particular size of ball shown, the line E is at right angles to the plane of the equatorial circle.

70 In Fig. 9 the rotative center of the equatorial circle is located on line E at the particular size of core shown. Line E is shown, in this figure, at an angle other than a right angle to the equatorial plane, to indicate that the plane of the 75 equatorial circle is changed as well as the rotat-

tive center, as the core increases in size during the winding.

Line E represents, also, a plane passing through all of the contact points at which the sphere is in contact with the several rollers when at rest, and, is also the focal plane of the axis of rotation which is changed during the winding operation.

Referring to Fig. 9 the contact between the sphere and rollers 14-14 and roller 25 are at 10 approximately where the line E intersects the circle S. As will be seen here, the contact between the roller 25 and the sphere S is further away from the horizontal center, while the contacts between the sphere S and rollers 14-14 15 are closer to the horizontal center of the sphere. It will also be noted that the diameter of roller 25, at the point of contact with the sphere, is larger than the diameter of rollers 14-14 at the point of contact of these rollers with the 20 sphere.

Due to these relative sizes or variations and locations of the holding rollers, as the size of the ball increases due to the winding operation, the roller 25 is operative or effective to push the ball 25 downward and thus bring the horizontal center of the sphere closer to the contact points on rollers 14-14 and further away from the contact point on the roller 25. With this downward movement of the ball, the lower part of the ball or sphere 30 will move to the left as it rolls over the operative face of rollers 14-14 and the upper part of the sphere will move to the right so as to maintain contact with roller 25.

This motion is caused by the increase in the 35 size of the ball and is a sort of rotary or swinging motion in clockwise direction and opposite to the general direction of winding as indicated by the arrow in Fig. 9. When this motion takes place, as the diameter of the ball increases during the winding operation, it has the effect of changing the line or axis E to become more nearly vertical from that which is shown in Fig. 9.

40 As the sphere is pushed downward by the roller 25 and forward by the rollers 14-14 as 45 above explained, the axis E remains substantially in the position shown in Fig. 9, except that it becomes more nearly vertical as just explained. This in effect produces a relative movement between the true center of the sphere and 50 the center of rotative shift as represented by the axis line or plane E. That is, the rotative axis about which the reciprocating motion, as indicated at F-F in Fig. 3, takes place is gradually 55 and continually moved away from the true center of the sphere as its diameter is increased due to winding.

When the rotative center of the equatorial circle is changed during the period of winding, or, when both the rotative center and the plane 60 of rotation are changed, then one or more of the supporting contact points should be permitted to have two or more directional motions, that is, a rotative motion to correspond with the general direction of winding, which is the polar circle, 65 and one or more other directional motions to correspond with the shift of the geometric center of the equatorial circle about the rotative center of said circle. This may take the form of a sliding motion as shown in and as will be explained 70 with reference to Figs. 7 and 8; or, it may be a pivotal rocking motion as shown in Figs. 9 and 10; or it may be any other suitable compound motion.

75 As indicated in the various diagrammatic illus-

trations, the invention may be embodied in many different forms, all of which essentially comprise a series of idler rolling members suitably mounted to permit their free rotation, in one or more directions, as they are driven by the core being wound, while maintaining or continually changing the axis or the plane of rotation of the pattern control motion or both.

The mechanical embodiment of the invention which appears best to illustrate the various motions involved and produces the greatest range of variation in the pattern of winding as the core increases in size, comprises a series of rollers mounted for free rotation in one or more directions. This furnishes a clear illustration of the change in the rotative center as well as the change in the plane of rotation of the equatorial circle of the core being wound. One such device is shown in Figs. 9, 10, 11 and 12.

Referring to Fig. 9 the invention is shown comprising an L-shaped bracket 8 having two sides 8a and 8b. Side 8a is provided with a stationary stud 9 having an eccentric enlargement 10 at one end by which it is held in bracket 8 by means of set screw 11. Side 8b of bracket 8 is provided with a hole in which a yoke 12 is pivoted. Side 8b is also provided with a screw hole 13 through which the device may be fastened to any suitable support on a winding machine.

The small end of stud 9 is provided with two taper rollers 14—14 with their small ends facing each other and journaled on stud 9 by means of ball bearings 15, two for each roller 14. These bearings are held in position by means of screw 16, washer 17 and separators 18 as will be clear from the illustration. The rollers 14 may be made of any suitable material and if desired may be provided as shown with some cushion material on their operative faces as indicated at 19. This cushion material may be canvas, felt, rubber, leather, or the like. The object is to prevent chafing or other damage to the hard core being wound. When a soft core such as a base ball core is wound of such filamentary material as wool or the like, then the rollers may be made entirely of metal or fiber without a soft cushion on their operative faces.

The rollers 14, 14 are independent of each other and are free to rotate at any speed and in any direction relative to each other about the stud 9.

The yoke 12 comprises a cylindrical portion 20 journaled in side 8b of bracket 8 and is held therein by the collar 21 and pin 22 (see also Fig. 11). The lower end of side 8b is provided with a slot 23, the sides of which act as a limit stop for the projecting end of pin 22, and thus prevent the yoke 12 from having excessive reciprocation, as will be obvious.

The upper end of yoke 12 is provided with a furcation 24 in which a fragmental spherical roller 25 is mounted for free rotation on a shaft 26 by means of ball bearings 27, 27 which are held in spaced relation by the spacer 28. Roller 25 is also provided if desired, with a cushion face 19 as were the taper rollers 14, 14 described above. As will be clear from the illustration, the roller 25 has a compound directional motion, that is, it is free to rotate on its axis 26 and is also free to swing about the axis 20 of the yoke 12.

The cup-like pocket formed between these rolls is adapted to receive the core to be wound and to hold it during the winding operation. By reason of the eccentric end 10 of stud 9 this pocket may be made larger or smaller by turning the

stud 9 by means of the screw driver slot 29 and clamping by the set screw 11 at any desired position. It will be clear, however, that if desired, mechanical means to enlarge or reduce the pocket-like opening during the winding operation may be substituted in place of the manual setting which is shown.

One of the objects of this adjustment is to provide a wide dimensional range for the device. For example, the device as shown in Figs. 9, 10, 11 and 12 has a dimensional range of from about 1 inch for the starting size core to about 2½ inches for the finished size core. When the stud 9 is turned about the eccentric enlargement 10 through approximately 180 degrees from that which is shown, then the range of the device is reduced to take a starting core of about ½ inch diameter and the finished core about 1¾ inches diameter. This is an important economic advantage of the invention because the device can be used, for example, to wind golf balls during one period and base balls during another period, and thus, one device will serve two purposes.

The axis of shift of the equatorial circle is located on line E, Fig. 9. As will be seen from the illustration, this line is at an angle other than a right angle to the conventional geometric plane of the equator, as well as being located away from its geometric center. It will be evident that as the diameter of the core being wound is increased during the winding operation, the axis in the plane as well as the plane of shift about the equatorial circle will continually change and thus the pattern of winding will also change. The change of pattern is due entirely to such change in the equatorial shift of the axis or in the plane change of the equatorial circle of the core being wound or both. It is entirely independent of any change, or lack of change, in the base pattern incorporated in the single driving member A, which itself is provided with means of changing its own base pattern.

When the rotative center of shift of the equatorial motion is located in the semi-sphere furthest away from the single driving member, then the actual shift along the equatorial circle will be less than that incorporated in member A, and, when the rotative center is located in the semi-sphere nearest to the single driving member A then the actual shift along the equatorial circle will be more than that incorporated in said member. Of course, the axis of shift may be located entirely outside of the equatorial circle, either to increase or to reduce the dimensional or angular shift incorporated in member A.

In Fig. 12 the lines C2 and C2 represent the contact lines at a given size of the core and these coincide with the lines C2 and C2 as shown in Fig. 4. The line passing through the centers of contact between the core being wound and the rollers 14, 14 is indicated as 30 in Fig. 4. The small circles 31 and 32 through which the line 30 is drawn represent the contact points when located on the major amplitude line C1. However, in practice, as shown in Fig. 12, the contact points should fall on the total amplitude line for the maximum size core to be wound, which are C2 and C2 for the right or left hand amplitude.

The contact point between the core and the roll 25 is shown in Fig. 4 at 33 and as this roll has a compound pivotal motion the contact point will swing to the right or to the left as indicated at 34 and 35, as the case may be. When the stud 9 is rotated about the eccentric 10, Figs. 9

and 10, then the distance between the contact lines 30 and 36 is reduced or increased, as the case may be. Also the line E, Fig. 9, is moved closer to or further from the geometric center 5 of the equatorial circle of the core and the plane angle of line E is changed, as will be evident from the illustrations.

In the figures, the core or sphere being wound is indicated at S and the filament which is 10 wound on the core is indicated as T. The various directions of motions and rotations are indicated with arrows, as will be obvious from the illustrations.

In the embodiment shown in Figs. 5 and 6, 15 there are provided four free disc-shaped idlers which may, if desired, slide along the lines 1, 2, 3 and 4 to increase or to reduce the pocket-like space formed between them adapted to receive the core to be wound. This sliding may be performed manually or mechanically, as may be 20 convenient, to conform with the dimensional range of size of the core to be wound. When such range is not excessive the discs may be mounted permanently for free rotation only. 25 Such is shown in my co-pending and above-identified applications.

In the embodiment shown in Figs. 7 and 8 the device shown comprises taper rollers 31, 31 which rotate freely on stud 38 and correspond in 30 action to rollers 14, 14 of Fig. 10. The free rotating rollers 39, 39 are free to rotate on their axes and are also free to slide on their respective studs 40, 40 and this action is similar to the action of roller 25 and yoke 12 in Fig. 9. In Fig. 8 only 35 one of the sliding rollers 39 and its stud 40 are shown.

The adjustment shown in Figs. 9 and 10 with respect to stud 9 and eccentric 10 may, if desired, be incorporated in one or both of studs 40 in 40 Figs. 7 and 8, and may be manual or mechanical, as may be desired, in winding cores within small or large dimensional range from the starting to the finishing size.

As will be noted with reference to Figs. 5 and 6, 45 the rotative center of the equatorial motion of the sphere, indicated by line E, is, practically, at the geometric center of the equatorial circle.

With reference to Fig. 7, the rotative center of the equatorial circle is variously between the line 50 E and the circumference of the polar circle. In this embodiment the plane of the equatorial motion is also changed, depending on whether the sphere, before reaching its finished size, rolls between rollers 31, 31 and the lower roll 39 or the 55 upper roll 39, as may occur when no adjustment is provided to keep the rollers 39, 39 in contact with the core at all sizes during the winding operation.

As shown in Fig. 12, the rotative center of 60 the equator is variously located between the geometric center and a final position indicated by line E, its exact location, as is the location of line E, depending on the size of the core at the particular time during the winding operation. The 65 plane E as shown by line E (Fig. 9) will also change with the size of the core during the winding operation, as will be obvious from the above description.

In operation, the core is placed in the pocket-like space formed by the rotative members, which 70 are driven by the core in a constantly changing direction and constantly changing speed relation with respect to each of these members, but at a uniform linear speed with respect to the peripheral speed of the core, in the resultant direc- 75

tion as imparted to the core by driving it through a single point.

It may be further explained, with reference to Figs. 9 and 12, that the sphere is in operative contact with only one of the rollers 14 and is in reality balanced between the driving member and one of the rollers 14. As the sphere is carried through a circular motion by the driving member the contact point is shifted from one of the rollers 14 to the other of the rollers 14, then to 10 the roller 25, and back again to the first of the rollers 14. When the sphere shifts itself as much as $\frac{1}{8}$ of an inch on the geometric center (in Fig. 12) this separation is so small that it is not visible to the eye. It may be seen indirectly 15 through a stroboscope tuned to the frequency of rotation of these rollers, which will show alternate variations in the speeds of rotation of rollers 14-14 and 25 as the sphere comes in contact with them.

While the diagrammatic illustrations shown in Figs. 1, 2, 3 and 4 are generic in nature and are applicable to the several embodiments shown in Figs. 5, 6, 7, 8, 9, 10, 11 and 12, the diagrammatic illustrations shown in Figs. 13 to 19, both 25 inclusive, are specific and are applicable only to the type of device shown in Figs. 9, 10, 11 and 12.

As previously explained, the axis of the equatorial shifting motion is located on line E. With reference to Figs. 13 and 14 the equatorial shifting motion is designated as 50 and is shown as a circle with the circumference at the driving contact point indicated at 51 and having the axis 52. The axis 52 intersects the geometric axis 53 at the same point where the axis E intersects the 35 axis 53, which is the focal point 54. Line E is referred to both as the axis and as the focal plane because it represents a section through a plane which passes through the three contact points of the idlers 14-14 and 25 and can be 40 shown only as a line. In constructing an embodiment of the invention the line E must be square to the axis 52 so as to permit free rotative motion of the sphere S about the axis 52 in the circular motion 50. Then, the free rotative 45 motion of taper rollers 14-14 and the free swinging motion of roller 25 about its axis 20 (see also Fig. 9) permit this to take place.

The free rotation of the roller 25 about its axis 26 and the free rotation of rollers 14-14 50 about their axes 9 will permit the sphere S to rotate in the general winding direction, or polar circle, (designated as 55 in Figs. 13 and 14). The axis of motion 55 is indicated at 56 (Fig. 14) and passes through the geometric center 57 of the 55 sphere S. The normal axis of the equatorial circle 58 is designated as 59, but the actual axis of rotation is the line E. Thus, in this invention, the effective axis of the equatorial circle 58 is located away from the geometric center 57 of the 60 sphere S and also at an oblique angle to the normal equatorial circle 58 in the plane indicated in Fig. 13, but parallel with the axis 56 of the polar circle 55 as indicated in Fig. 14, and square to the axis 52 and 53 in the plane indicated in 65 Fig. 14, while square to the axis 52 and at an oblique angle to the axis 53 in the plane indicated in Fig. 13. As will be seen from Fig. 13, as the ball is wound and becomes large and larger, the axis E will remain substantially in its position indicated, except change the angle of obliquity as previously explained, while the geometric center 57 will move to the left, assuming for the moment that the driving member A moves to the left as the ball increases in size, and thus increase 70 75

the distance between the focal point 54 and the geometric center 57. The equatorial shift caused by the circular motion 50 is made along the circumference of a circle 60 (Fig. 14) which has a 5 radius equal to the distance between the focal point 54 and the contact point 51, as will be evident from the illustration. The increase in the size of the ball during the winding operation will move the contact point 51 away from the 10 focal point 54 in the same manner the geometric center 57 is moved, but to a greater extent, and thus the circle 60 will become larger, and will require a larger number of turns to be made by the circular motion 50 to make one complete turn 15 in the circle 60.

The increase in the size of the circle 60 will be greater than the increase in the size of the sphere S, due to the winding operation, because both the geometric center 57 is shifted away from 20 the focal point 54 as well as the contact point 51 is shifted away from the geometric center 57 due to the increase in the size of the ball S. The greater or lesser division of the motion 50 in the circle 60 as shown in Figs. 13 and 14 is also shown 25 in Figs. 1 and 3 in which the angular turn C represents the radius of the motion 50 as previously explained.

With motions along circles 50 and 55 operating on the ball S, the ball will run true on its geometric center 57 in both planes as indicated in 30 Figs. 13 and 14, but the spacing about the equatorial circle 58 will vary in accordance with the location of the focal point 54, which in turn is the controlling element in the diameter of circle 35 60. This may be seen clearly with reference to Figs. 14 and 19. That is, considering the polar axis 56 and designating the intersecting points of this line with the circumference on the ball as points 61 and 62 (as by say painting a red 40 and a white spot on the ball) and following these spots until the circle 60 has made one complete turn (in effect) by making the required number of turns of motion 50 and 55, then, it will be seen that the circumference of the circle 60 will be, 45 so to speak, gathered up into a unique curve, and the polarity of the axis 56 reversed. That is, point 61 will take the place of point 62 and point 62 will take the place of point 61. This shift has been referred to previously as the shift in the 50 axis of rotation in the pattern control plane which is the plane in which Figs. 1, 2 and 14 are taken and is indicated as line 53 in Figs. 13 and 17. In Fig. 19 the curve described by the point 61 is 55 shown completed for both the near side and the further side of the ball S until it reaches the position formerly occupied by the point 62, while the curve for point 62 is shown only on the near side of the sphere S. Fig. 19 may be considered as a reproduction as by a motion picture of the 60 paths of points 61, 62 actually taken during a given cycle in an operating device of the type described and with such relative proportions for the motions as will produce this form of curve.

However, as will be evident from the illustrations, the larger the diameter of the pattern control circle 60 with relation to the diameter of the ball S the more complex will be the form of the curve 61 shown in Fig. 19. Also, the closer the spacing of the wound filament will be along the 65 normal equator 58, because it will take more turns for motions 50 and 55 to complete one turn of the circle 60, which in turn corresponds to one reversal of the polarity of the axis 56. The developed length of curve 61 shown in Fig. 19 will 70 correspond to the developed circumference of the 75

circle 60 shown in Fig. 14, when drawn to equal scale.

Fig. 17 shows a third circular motion 63 superimposed over the motions 50 and 55. Figs. 16 and 18 illustrate the division or compound movement of the axis of this motion 63 and for clearness of illustration this division will be explained analytically.

Referring to Fig. 16 (which is a diagrammatic illustration of Fig. 9) the axis of motion 63 is indicated as 64 and, as will be seen, it coincides with the equator 58 and axis, or plane, 53 in the plane represented by Fig. 16. Axis 64 is, also, square to axis 59 but forms an oblique angle with the focal axis, or plane E.

Due to this oblique angle formed with the axis E by the axis 64 of motion 63, and due to the fact that rollers 14-14 can rotate about one axis only, the axis 64 is caused to reciprocate up and down as indicated by the lines 65 for up and 66 for down. This up and down reciprocation takes place about the geometric center 57 of the ball S. Analytically speaking, this up and down reciprocation of axis 64 is an addition or a subtraction to and from the linear speed of motion along the 25 circle 55 which rotates about the axis 56 which in turn passes through the geometric center 57. And, by this change in the linear speed of motion along the circle 55 the relation between motions along circles 55 and 50 is constantly modified 30 within the limits of reciprocation indicated by lines 65 and 66.

This is a partial or divisional modification of the 35 relation between the motions along circles 50 and 55, and is caused by the oscillation of the axis 64 about the geometric center 57. The change in 40 relationship between the motions along circles 50 and 55 is, thus, caused by a change in the linear speed of motion along circle 55 through the addition or subtraction of a portion of the motion 45 along circle 63.

In Fig. 18 a second partial modification of lesser 45 magnitude between the motions along circles 50 and 55 is shown. In contradistinction to the partial modification shown in Fig. 16, in Fig. 18 the motion along circle 50 is modified, with relation to the motion along circle 55. (Fig. 18 is a plan view of Fig. 16.)

Referring to Fig. 18, the axis 64 of motion along 50 circle 63 is shown passing through both the geometric center 57 and the focal point 54, the plane of Fig. 18 being oblique to the axis 52 and the plane axis E of Fig. 16. Analytically speaking, the motion along circle 63 then, in the plane of Fig. 18, will cause the axis 64 to oscillate, pivoting about the focal point 54 as indicated at 55 67 and 68 and as will be clear from the illustration.

The oscillation of the axis 64 about the focal point 54 will cause the geometric center 57 to 60 oscillate about the point 54 with the radius 69, in a curved path indicated as 70, and thus, the whole ball will oscillate back and forth as indicated by the angular displacement F-F (see also Fig. 3) and the normal equatorial circle displacement shown in dotted lines at 58 and B.

By this angular oscillation F-F of the axis 64, the geometric center 57 is moved to the points indicated as 71 on the displaced axis 67 and as 72 on the displaced axis 68. And thus, as previously 70 stated, the motion along circle 63 will modify the motion along circle 50 with relation to motion along circle 55 by shifting the axis of movement. That is, by the shift in the axis of movement of the motion along circle 63 an alternate and var- 75

ious magnitude of change in the relation of the other motions is made.

As the geometric center 51, as shown in Fig. 16, is moved into the positions 71 or 72, as shown in Fig. 18, the oscillation (as shown in Fig. 16) of the axis 64 may take place between the modified geometric center positions as indicated with the points 71 and 72 in Fig. 18. The pivotal oscillation of axis 64 about the focal point 54 is permitted by the swinging action of roller 25 about its axis 20 (see Fig. 9) and the resilient cushions 19, 19 and 19 of rollers 14, 14 and 25. The pivotal oscillation of axis 64 about the geometric center 51 is permitted by the free rotation of roller 25 about its axis 26 and the free rotation of rollers 14, 14 about their axes 9 (see Fig. 9). Any number of motions may be used, and as previously stated, the method of causing the member A to describe the desired compound motion forms no part of this invention. Such methods are fully described in my co-pending and above identified applications.

While certain embodiments of the invention have been described in detail in order to illustrate the principles of the invention it is to be understood that the invention may have various embodiments within the limits of the prior art and the scope of the subjoined claims.

I claim:

30 1. The method of changing the pattern of winding filament on spherical cores, which comprises, supporting said sphere in a pocket, driving said sphere through a single point to turn it about its geometric center while simultaneously 35 winding filament thereon, and simultaneously changing the relation between said driving point and the support to turn the sphere also about a center other than said geometric center.

2. The method of changing the pattern of 40 winding filament on spherical cores, which comprises, supporting said sphere in a pocket, driving the sphere through a single point, and winding filament on said core while moving the core by action through the single driving point about 45 two or more axes, at least one of said axes being located away from the geometric axis of the core.

3. The method of changing the pattern of 50 winding filament on spherical cores, which comprises, supporting said sphere in a pocket, driving the sphere through a single point to move it about two or more axes, simultaneously winding filament on the core, and simultaneously changing the relation between certain of said axes away from each other and away from the driving point.

4. The method of changing the pattern of 55 winding filament on spherical cores, which comprises, supporting said sphere in a pocket, driving the sphere through a single point to move it about two or more axes, simultaneously winding filament on the core, and simultaneously changing the relation between certain of said axes away from each other and toward the driving point.

5. The method of changing the pattern of 60 winding filament on spherical cores, which comprises, supporting said sphere in a pocket, driving the sphere through a single point to move it about two or more axes of a given initial angular relation, simultaneously winding filament on the 65 core, and simultaneously changing the angular relation between some of said axes.

6. The method of changing the pattern of 70 winding filament on spherical cores, which comprises, supporting said sphere in a pocket, driving the sphere through a single point to turn

it about two axes both of which at times pass through the geometric center of the sphere, simultaneously winding filament on the sphere to increase its diameter, maintaining one of said axes at the geometric center of the sphere, and simultaneously moving the other axis away from the geometric center of the sphere.

7. The method of changing the pattern of 75 winding filament on spherical cores, which comprises, supporting said sphere in a pocket, driving the sphere through a single point to turn it about two or more axes, simultaneously winding filament on the sphere to increase its diameter, and simultaneously moving one of said axes about the geometric center of the sphere and 80 about a second center located away from the geometric center.

8. The method of changing the pattern of 85 winding filament on spherical cores, which comprises, supporting said sphere in a pocket, driving the sphere through a single point to turn it about two or more axes having a given initial angular relation, simultaneously moving one of said axes about two separate centers, and simultaneously changing the angular relation between some of said axes.

9. The method of changing the pattern of 90 winding filament on spherical cores, which comprises, supporting said sphere in a pocket, driving the sphere through a single point to turn it about an axis passing through the center of the sphere, simultaneously winding filament on said sphere, and simultaneously moving the sphere about an axis which at times is located 95 away from the geometric center.

10. Apparatus for changing the pattern of 100 winding filament on spherical cores, comprising in combination, means for driving a core through a single point on its surface, and means forming a pocket for holding the core, said holding means including a pair of rollers having only rolling movement on one side of the core, and a roller having rolling movement and a swinging movement on the other side of the core.

11. Apparatus for changing the pattern of 105 winding filament on spherical cores, comprising in combination, means for driving a core through a single point on its surface, and means forming a pocket for holding the core, said holding means including a pair of rollers having only rolling movement on one side of the core, and a roller 110 having rolling movement and another movement on the other side of the core.

12. Apparatus for changing the pattern of 115 winding filament on spherical cores, comprising in combination, means for driving a core through a single point on its surface, and means forming a pocket for holding the core, said holding means comprising a pair of conical rollers having their small ends toward each other on one side of the core, and a single spherical roller on the other 120 side of the core, the conical rollers having only rolling movement and the spherical roller having rolling movement and also a swinging movement.

13. Apparatus for changing the pattern of 125 winding filament on spherical cores, comprising in combination, means for driving a core through a single point on its surface and imparting to it a motion which is the resultant of three separate circular motions, and means forming a pocket 130 for holding the core, said holding means allowing the core to have free movement in one direction but restraining its movement in the other directions.
